YARN TENSION FOR AUTOMATIC SHUTTLES

Allan M. Sergeson, Philadelphia, and Daniel B. Meehan, Aston Mills, Pa.

Application August 29, 1932, Serial No. 630,926

4 Claims. (Cl. 139—217)

The principal object of this invention is to provide an efficient yarn tension for automatic or self-threading shuttles.

To this general end, a more specific object of the invention is to provide a tension of the stated character which shall insure immediate entrance of the yarn into the tension in the normal re-threading operation.

A further and specific object of the invention is to provide a tension of the stated character that shall be highly efficient for all characters of yarn, including the high twist variety.

Still another object of the invention is to provide a tension of the stated character that will not tend to accumulate lint and dirt and which shall be practically non-clogging.

A still further object of the invention is to provide a tension that shall be so positioned relative to the self-threading thread block of the shuttle as to permit a normally strong construction for the said block.

The invention further resides in certain structural features and arrangements hereinafter set forth and illustrated in the attached drawings, in which:

Figure 1 is a plan view of one end of a shuttle equipped with a tension made in accordance with our invention;

Fig. 2 is a section on the line 2—2, Fig. 1;

Fig. 3 is a section on the line 3—3, Fig. 1;

Figs. 4, 5, 6 and 7 are, respectively, views in perspective of elements of the tension device shown in the preceding figures;

Figs. 8 and 9 are, respectively, sectional views corresponding to Fig. 2 but illustrating modifications within the scope of the invention;

Figs. 10, 11 and 12 are views in perspective of elements of the tension illustrated in Fig. 8;

Fig. 13 is a view in perspective of an element of the tension illustrated in Fig. 9, and

Fig. 14 is a section on the line 14—14, Fig. 1.

With reference to the drawings, 1 is a shuttle of standard form comprising the usual adjustable bobbin 2 and self-thread block 3. The block illustrated is also essentially of standard form and occupies the usual position within the shuttle, to which it is anchored in the usual manner by means of a screw 4. As illustrated, the block 3 has in its upper surface a longitudinal threading slot 5 located adjacent one side of the block body, this slot entering the longitudinal chamber 6 of the block. As illustrated in Fig. 2, the entrance slot 5 is bounded on one side by a depending lip 7 which overlies and forms a cover for the chamber 6. The slot 5 is so ar-

ranged in the block that the yarn drawn from the bobbin 2 with a substantially circular motion will tend naturally to pass downwardly therethrough into the chamber 6 in which it is confined by the lip 7.

In accordance with our invention, we provide at the inner end of the block 3 an undercut recess 8, see Fig. 3, within which is located our novel tensioning device. As shown in Figs. 2 to 7, inclusive, this tension comprises a body or frame member 9 formed in the present instance of pressed metal. This body portion 9 comprises an upstanding arm 11 which, as shown in Fig. 2, bears against one wall of the shuttle recess within which the thread block 3 is located. From the bottom of the arm 11 a base portion 12 extends to the bottom of an oppositely arranged arm 13, this arm occupying a slot 10 in the opposite wall of the thread block-receiving recess of the shuttle, and the base 12 bearing upon the bottom wall of said recess. The arm 13 at its upper end turns inwardly and downwardly to form an inclined abutment 14, the terminal end of which lies adjacent the upper surface of the base member 12 and is extended in an offset 15 along the upper face of the base member 12 to the inner face of the arm 11.

As clearly shown in Fig. 4, the upper end of the arm 11 is provided with a notched recess 16 and with an elongated aperture 17, while the inclined abutment 14 is provided adjacent the upper end thereof with a relatively small indentation or recess 18, and below this recess and in a position diagonally opposite the opening 17 of the arm 11, with a circular opening 19.

In assembly and as shown in Fig. 2, this body member is closely confined within the undercut recess 8 of the block 3, and between the walls of this recess and the side and bottom walls of the recess in the shuttle occupied by the block 3. It will be noted that the inturned upper end of the arms 11 and 13 of the body portion engage the top bounding wall of the undercut recess 8 of the block 3, and that the inclined abutment 14 is so formed that its upper end lies immediately adjacent the bottom of the slot 5 in the block through which, as previously set forth, the yarn from the bobbin 2 passes to the longitudinal chamber 6 of the block. The arrangement is such that from the lower end of the slot 5 the abutment 14 extends diagonally downward so as to intersect the end of the recess 6.

The tension device further comprises an element 21, see Fig. 5, which as shown in Fig. 2 is adapted to lie against the surface of the abut-

ment 14. The member 21 is angular in form, and the arm 22 thereof which lies against the abutment 14 is provided with a projecting tongue 23, which in assembly registers with the recess 18 of the said abutment, and with an opening 24 which registers with the abutment opening 19. The arm 22 is provided at each side with wings 25 slightly angularly disposed with respect to the intermediate portion of the arm so that portion of the member 21 which adjoins the abutment 14 in effect is somewhat convexed. The other arm 26 of the member 21 extends in assembly away from the abutment 14, and the extremity thereof occupies a position within the recess 16 at the upper end of the arm 11 of the body member. This arm 26 of the member 21 is also provided with a depending lug 27 which in assembly constitutes a relatively large bearing for the member 21 upon the adjoining surface of the block 3, thereby preventing abrasion of either the block or the element due to frictional contact and preventing the formation of wire edges that might adversely affect the yarn.

As shown in Fig. 2, the member 21 is held in position with respect to the body member by a pin 28 shown in perspective in Fig. 6. This pin passes through a port in the body of the shuttle 1 and through the apertures 17 and 19 of the body member of the tension and through the opening 24 of the member 21. The outer end of the pin 28 is threaded, as clearly illustrated, into the shuttle body, the outer end surface of the pin being socketed for reception of a suitable wrench. The pin 28 is also provided with a shoulder 29 which forms a seat for one end of a spring 31, the other end of which spring bears upon the outer face of the arm 22 of the member 21, as shown in Fig. 2. The opening 24 in the member 21 is sufficiently larger than the pin 28 to permit substantially free movement of the member in a direction longitudinally of the pin, and this movement is not restricted by the body member of the tension. It is apparent that by threading the pin 28 more or less deeply into the shuttle 1, the effective tension of the spring 31 upon the member 21 tending to force that member against the abutment 14 may be regulated.

As shown in Figs. 1 and 2, wherein the yarn is designated by the reference numeral 32, the latter normally is adapted to pass between the opposed faces of the abutment 14 and the arm 22 of the member 21, and thence through the chamber 6 of the block 3. Resilient pressure is thus applied to the yarn through the medium of the spring 31, and the member 21, and the force of this pressure may be regulated as previously described by adjustment of the pin 28. The pin 28 itself limits the downward movement of the yarn 32 between the surfaces of the tension between which it is confined, and the tongue 23 on the member 21 tends to limit the upward movement of the yarn 32 so that the latter is effectively confined between the opposed tension elements. In this manner, influences tending to displace the yarn from the tension are counteracted.

An important characteristic of the device resides in its relatively high efficiency as compared with prior devices of this general character in the self-threading operation. So far as we are aware, there has never, prior to our invention, been devised a tension for self-threading shuttles which will operate to take hold of the yarn

immediately upon the entrance thereof to the thread block of the shuttle. Two or three picks were frequently required before the yarn properly entered the tension, with consequent undesirable effects upon the fabric. With our device, there is practical assurance that the first pick will result in the yarn not only entering the block but also the tension, so that the woven product is absolutely uniform. This is due not only to the structure of the tension itself but to its arrangement in the assembly and its relation to the slot 5 of the block. Yarn passing into the slot necessarily follows the course of least resistance which leads downwardly between the resilient opposed elements of the tension. This is due also in part to the position of the tension with respect to the eye and to the adjacent end of the bobbin, it having been found that this point is most favorable by reason of the relative freedom of the yarn at this position from the eccentric movements, which in the prior devices are in some part responsible for the relatively low efficiency previously set forth.

Another desirable characteristic of our device resides in its substantial freedom from clogging due to accumulations of lint and dirt. The tension while retaining the necessary intimate association with the thread block is so exposed to the air currents as to insure an efficient clearing away of the loose lint and dirt which otherwise might tend to accumulate and clog the device. It will be noted further that the tension is so located in the thread block of the shuttle that it does not in any way interfere with the sturdiness of the latter. Heretofore it has been the practice to install tensions in the body of the block in such manner as to materially weaken the walls, these blocks being thereby rendered subject to rupture under the heavy stocks to which shuttles are subjected. Tensions made in accordance with our invention are also well adapted to many types of yarns, and may be used to advantage with yarns of high twist which are not readily handled in prior tension devices of this general character.

In Fig. 8, we have illustrated a modification within the scope of the invention. The structural form and disposition of the tension in the assembly are in this instance essentially the same as that previously described. The pin 28, however, shown in Fig. 6 is replaced by a pin 35 corresponding to the pin 28 with the threaded portion thereof removed. The pin 35 does not enter the body of the shuttle and is confined entirely to the body member of the tension as shown in Fig. 9. A spring 36 used with this pin and corresponding to the spring 31 previously described not only acts to hold the member 21 of the tension against the abutment 14 but also holds the pin 35 in position. The body member of the tension shown in Fig. 10 is in this instance essentially the same as that previously described and illustrated in Fig. 4, and the parts thereof are designated by the same reference numerals previously used. It will be noted that in this case as well as in that previously set forth the opening 17 through which the pin projects is elongated so as to permit freedom of movement of those portions of the pins 28 or 35, as the case may be, which in assembly are positioned therein. This avoids the necessity of careful machining in aligning the openings 17 with the openings 19 in the abutment 14. The mode of operation of this embodiment of our invention is in all respects similar to that previously described, this form of

device differing from the other solely in the fact that the tension is not adjustable.

In Fig. 9, a still further modification is illustrated. This tension also is essentially the same as those previously set forth and differs therefrom primarily in the provision of an arm 37 provided on the tension element 21a, this arm as shown in Fig. 9 being so positioned as to prevent the yarn passing through the tension from coming into contact with the pin 28 or falling into the area of the openings in the opposed tension elements through which the pin extends. Silk and other delicate yarns are sometimes abraded by contact with the edges of these openings, and such abrasion is prevented by provision of the said arm 37 which functions as described.

In the use of this tension, we have found it desirable, see Figs. 1 and 14, to so arrange the brushes 38, the function of which is to prevent undue lateral whip of the yarn leaving the bobbin, so that they do not contact with the bobbin, thus leaving a space through which the yarn may pass freely. Where the brushes touch the bobbin, there is a tension effect upon the yarn as it passes between the bobbin spindle and the brush which is added to the tension of the normal tension device. We have found that the tension device described above is so efficient and affords such a uniformity of strain upon the yarn that any further tensioning of the yarn is undesirable. By removing the brushes from contact with the bobbin, the entire tensioning of the yarn resides in the tension device. The brushes 38 at the same time, however, are effective to prevent the undesirable lateral whipping of the yarn.

We claim:

1. In a self-threading shuttle, the combination with a threading block having a longitudinal yarn-receiving passage, a slot in the upper end of said block adjacent one side of said passage and communicating with the latter, a tensioning device at one end of said block comprising a relatively fixed open frame having an arm 45 extending diagonally across one end of said passage and with its upper end adjoining the said slot, and a thin floating bar paralleling and adapted to contact the face of said diagonal portion, a pin extending through the lower end of said floating and diagonal elements, a spring carried by said pin and tending to force said floating bar against said diagonally relatively fixed arm, and an arm extending from the upper end of said floating bar and having its terminal end loosely confined within a recess in said frame, said bar being substantially free to move to and from the opposed diagonal arm of said frame,

while being restrained from transverse displacement at both terminal ends.

2. In a tension for self-threading shuttles, the combination with a thread block having a longitudinal yarn-receiving passage and in its upper 5 end a slot positioned adjacent one side of said passage and communicating with the latter, a yarn-tensioning frame at one side of said block relatively fixed with respect to the latter, said frame comprising an inclined portion the upper 10 end of which lies adjacent the said slot and extending diagonally across the end of said passage, an angular element having one arm paralleling and adapted to contact the face of said diagonal frame portion, and a second arm extending from the upper end of the first-named 15 arm and away from said diagonal frame portion, means engaging only the outer terminal end of each of said arms to prevent transverse displacement of the element with respect to the frame, 20 and a spring resiliently forcing said element towards the opposed surface of said frame.

3. In a tension for self-threading shuttles, the combination with a thread block having a longitudinal yarn-receiving passage and in its upper 25 end a slot positioned adjacent one side of said passage and communicating with the latter, a yarn-tensioning frame at one side of said block relatively fixed with respect to the latter, said frame comprising an inclined portion the upper 30 end of which lies adjacent the said slot and extending diagonally across the end of said passage, an angular element having a portion paralleling and adapted to contact the face of said diagonal frame portion, means engaging both 35 terminal ends of said element to prevent transverse displacement thereof with respect to the frame, a spring resiliently forcing said element towards the opposed surface of said frame, and a flange carried by one arm of said element and 40 constituting an extended bearing for said element upon the block.

4. A self-threading shuttle comprising a bobbin, a thread block positioned adjacent one end of the bobbin and having a longitudinal yarn-receiving passage, said thread block having also an undercut recess in the end thereof adjoining the bobbin, the inner end of which recess is defined by a substantially plane vertical wall intersected by said passage, and a yarn-tensioning device 45 confined in said recess and comprising a substantially rigid frame secured in abutment with said wall, and a thread-engaging element resiliently supported in the frame in substantial alignment with said passage. 50
